BOILER

John Cook, Buffalo, N. Y.

Application December 10, 1942, Serial No. 468,601

5 Claims. (Cl. 122—30)

My invention relates to a boiler.

One of the objects of my invention is to provide a boiler heating system wherein a rapid circulation of comparatively clean water is assured through the boiler and accessories, and wherein impurities in the water will be trapped prior to circulating through the system.

Another object of my invention is to provide means whereby cold water as a source of supply is fed to the boiler and enters a settling tank or chamber before being delivered into the boiler proper, so that the cold water entering the settling tank or chamber will immediately contact the hot water circulating through the system and cause separation of foreign matter and the settling of such matter to the bottom of the settling tank or chamber.

A further object of my invention is to provide a boiler system wherein rapid circulation of water through the system will keep the boiler clean and will generate steam much quicker than has heretofore been possible.

A still further object of my invention is to provide, in a boiler system, a settling-tank or chamber and to so connect the tank or chamber with the boiler proper that a rapid circulation of water caused thereby will minimize the tendency of foreign matter or impurities to lodge against the walls of the boiler proper; this being accomplished by delivering cold water into the settling-tank or chamber at a medial point, taking the water from the tank or chamber at least in part at substantially the same level and feed the same to low points of the water-chamber or chambers of the boiler and returning the water from a high point of the water-chamber or high points of the various water-chambers of the boiler to a high point of the settling-tank or chamber.

A still further object of my invention is to include in my improved boiler system, water-chambers at opposite sides of the combustion-chamber, to provide spaced-apart legs on the boiler element so that they are disposed at the front and rear of the combustion-chamber, to provide water-jackets which serve as side walls of the boiler-furnace and which are spaced in relation to said water-chambers to provide fuel-compartments which feed the fuel into the combustion-chamber underneath said water-chambers, to provide said chambers and jackets with water-inlets to receive water from a settling-tank receiving the initial supply of water to the system, and to connect high points of said water-chambers and water-jackets with high points of the boiler proper and also connect a high point

of said boiler proper with a high point of the settling-chamber; thus assuring a rapid circulation of water through the boiler system and separation of impurities in the water within the settling-chamber at the point of admixture of the cold water fed to said settling-chamber with the hotter water circulating through said chamber and through the various water-containing elements of the boiler-furnace.

10 It is well known that water from different sources vary in impurities and that some waters have more sediment than others, such as magnesium, which when heated turns into a chalky substance and adheres to the walls of water-chambers and pipes and clogs up such parts, somewhat similar to lime. Impurities of this kind will in my improved boiler system, due to the particular point of entrance of the water from its source into the system and to the connections made between the various parts of the system, separate from the circulating water in the system and settle at a low point, where it can be easily blown off and assurance had of comparatively clean water circulating through the system.

With the above and other objects to appear hereinafter my invention consists in the novel features of construction, in the arrangement and combination of parts and in the manner of connecting such parts, all as will be hereinafter described and more particularly pointed out in the appended claims.

In the drawings—

Fig. 1 is a combination view, showing one-half of my improved boiler system in front elevation and one-half in transverse section; the section being taken centrally through the boiler proper, its combustion-chamber and one of the side fuel-chambers.

40 Fig. 2 is a longitudinal section through the boiler-furnace of the system and the settling-tank associated therewith, taken on line 2—2, Fig. 1, looking in the direction of the arrow crossing said line.

45 Fig. 3 is a top plan view of the same.

Fig. 4 is a horizontal section taken on line 4—4, Fig. 2.

Fig. 5 is a horizontal section taken on line 5—5, Fig. 2.

50 Fig. 6 is a horizontal section taken on line 6—6, Fig. 1.

Now referring to the drawings in detail, the reference numeral 6 designates the boiler-furnace which may be used for the generation of steam for power or heating purposes, or for the

circulation of water in a water-heating system, as will be explained hereinafter.

This boiler-furnace comprises a boiler proper, designated 7, which may vary in form and construction, but as shown in the drawings comprises a cylindrical vertical tubular boiler 8 having as a part thereof two depending water legs 9 and 10 which are parallel to each other and spaced-apart, as best shown in Fig. 2. The cylindrical portion of said boiler has a bottom-wall 11 and a top-wall 12 and spaced from said top-wall an intervening-wall 13 which serves as the top of the water or steam space of the boiler. Heat-flues 14 connect said bottom-wall 11 with the wall 13. The lower ends of these flues open into the space between the parallel depending legs 9 and 10, while the upper ends thereof open into the space between the intervening-wall 13 and the top-wall 12, said last-mentioned space serving as the smoke-box for the boiler and having a smoke-pipe 15 extending laterally therefrom for connection with a chimney.

The water-space in the boiler is continuous from the bottom of the parallel depending legs 9 and 10 to the intervening-wall 13, which may be considered the actual upper end of the boiler proper, since the smoke-box may be built onto the upper end of the boiler, although not so shown.

The front water leg 9 is provided with a door-opening 16 and this opening leads to the space between said leg and the rear leg 10, which space serves as a combustion-chamber, as will be explained hereinafter. The water legs 9 and 10 have extensions which are continued downwardly as a single thickness of metal and serve as walls to support the boiler from the floor on which the boiler system rests. In this manner a space, such as 17, is provided at the bottom of the boiler having said extensions serving as front and rear walls, designated 18 and 19. This space is closed at the sides by walls 20 and 21 and the space so confined between walls 18, 19, 20 and 21 is to be divided to serve as ash-pits, as will appear hereinafter.

The bottom-wall 11 of the tubular-boiler proper serves as a bridge-wall connecting the two parallel depending water legs 9 and 10 at the front and rear of the boiler-furnace and directly beneath this bridge-wall the combustion-chamber 22 is arranged. A horizontal rocking-grate 23 serves as the bottom of this combustion-chamber and it is supported by vertical-walls 24 and 25 which divide the space 17 at the bottom of the boiler-furnace into three ash compartments, comprising two side ash-compartments 26 and an intermediate ash-compartment 27; the latter arranged beneath the rocking-grate 23. Although in the drawings I have shown only one side ash-compartment, it is apparent that a similar compartment is provided at the opposite side of the boiler-furnace.

28 designates water-chambers which serve as sides for the combustion-chamber 22 and outside of these water-chambers, fuel-chambers 29 are provided; these being arranged between the water-chambers 28 and water-jackets 30 which serve as continuations of the side walls 20 and 21.

Inwardly inclined rocking grates 31 extend from the lower ends of the water-jackets 30 to the upper ends of the vertical-walls 24 and 25 and the inner ends of these grates are supported on shelves or ledges 32 extending outwardly from said walls.

From the foregoing it will be apparent, that

the bottom or bridge-wall 11 of the tubular boiler 8 serves as the top-wall of the combustion-chamber, the depending water legs 9 and 10 as the front and rear walls thereof and the water-chambers 28 as the side walls, and it is to be noted that the lower ends of the water-chambers are spaced from the grates 23 and 31 to provide fuel-feeding throats 33 leading to the lower end of the combustion-chamber.

10 It is also to be noted that the water-chambers are directed upwardly and outwardly from their lower ends and have their upward ends extending into the open, as at 34. The water-jackets 30 are also inclined upwardly and outwardly, but 15 at a lesser angle than the water-chambers so that the fuel-chambers are gradually increased in width downwardly toward the rocking grates 31, which serve as the bottoms of said fuel-chambers; thus preventing packing of the fuel within 20 the chambers. By reason of the rocking grates 31 being inclined downwardly and inwardly, the fuel automatically gravitates toward the center of the boiler-furnace so that the two supplies of fuel at opposite sides of the boiler-furnace gravitate toward the center of the combustion-chamber by passing through the feed throats 33, such 25 movement of the fuel being accelerated when rocking the grates 31. Such action of the grates also serves to free the fuel of any ashes on said 30 grates due to the fact that burning of the fuel at the lower ends of the fuel-chambers takes place at times.

By suitable rocking mechanism, such as generally designated by the numeral 35, the grate 23 35 can be rocked or shaken when required and each of the rocking grates 31 is also provided with mechanism 36 for rocking the same. Ashes from the side grates 31 enter the side ash-compartments 26 and ashes from the intermediate grate 40 23 are delivered into the intermediate ash-compartment 27.

Air-inlet tubes 37 extend through the water-jackets 30 and these tubes are closed at their inner ends and provided with openings 38, as 45 best shown in Fig. 2. Their outer ends have dampers 39 applied thereto for regulating the supply of air therethrough or for entirely shutting off the supply of air, as may be desirable. When large size coal is used the tubes may be 50 open at both ends, as shown in Fig. 6.

The boiler-furnace thus far described is one especially adapted for use in connection with other features of my invention and is believed to possess advantages not inherent in other boiler-furnaces when associated with the other features 55 in my invention to be presently referred to. It is also to be understood that such other features of my invention may be associated with different types of boilers, with the assurance that advantages will be derived therefrom not inherent in any other boiler heating system.

I associate with my improved boiler-furnace, or any other boiler-furnace, a settling-chamber 40 which may be supported in any suitable manner and which is of a comparatively large water capacity. A medial point of this settling-chamber is connected with the lower ends of the water-chambers 28 by water-feed pipes 41. Connection is also made between the upper and lower ends 70 of the settling-chamber 40 and the water-jackets 30 by water-feed pipes 42, and connection is made between said settling-chamber and the lower end of the boiler proper, preferably with the lower end of the water leg 10, by a water-feed pipe 43. 75 Connection is furthermore made between the

upper ends of the water-chambers 28 and a comparatively high point of the boiler, preferably with the tubular boiler portion 8, by water-circulating pipes 44 and these water-circulating pipes have connection between their ends, as at 45, with the upper ends of the water-jackets 30 by water-circulating pipes 46. The boiler is also connected with the upper end of the settling-chamber 40 by a hot-water return pipe 47 which is comparatively large so that it will have a capacity equaling the aggregate capacity of the several water-feed and water-circulating pipes above referred to and thus assure a rapid circulation of water through the boiler heating system.

In the drawings I have shown the level of the water within the boiler a distance below the wall 13 thereof, as indicated at 48, so as to provide a steam space 49 above the water. A steam-delivery pipe 50 is connected to the boiler so as to receive steam from this steam space, to be utilized for heating, or power purposes.

A water-supply pipe 51 for the heating system is connected with the settling-chamber 40 a distance from its lower end and in the drawings I have shown connected to this water-supply pipe a return water pipe 52 which, however, is not used when utilizing the boiler-furnace as a steam generator. It is, however, to be understood that this system can be employed for hot-water heating purposes in which case the entire boiler and its water connections would be filled with water and the steam-delivery pipe 50 would be utilized as a water-delivery pipe, supplying hot water to various radiators in a heating system or other objects utilizing hot water, from which the water so utilized is returned to the settling-chamber 40 through the return-water pipe 52 which would always be used in a hot-water heating system and would be omitted, plugged up, or shut-off when utilizing the system as a steam generating system. In any event, it will be found necessary to supply additional water to the heating system, whether used as a steam-generating system or a hot-water heating system and in all cases the water-supply or delivery to the settling-chamber is at a considerably lower temperature than the water circulating within the system.

When using the system for generating steam, water supplied thereto through the water-supply pipe 51 will be at a much lower temperature than the water circulating through the system and, of course, when utilizing the system as a water-heating system, the water returned through the return-water pipe 52 will be comparatively cool as it enters the settling-chamber, especially so when additional cold water commingles with the return or circulating water under automatic control, as will be understood by those familiar with the art to which this invention relates.

When using the system as a steam-generating system, the hot water within the boiler passes downwardly into the upper end of the settling-chamber and from the latter passes through the water-feed pipes 41, 42 and 43 into the various segregated chambers or water-containing portions of the boiler-furnace, rising upwardly from the depending legs 9 and 10 into the cylindrical boiler portion 8 and rising also from the lower ends of the water-chambers 28 through the circulating pipes 44 connected to the upper ends of said chambers and from the upper ends of the water-jackets 30 through the water-circulating pipes 46 and 44 into the boiler proper, from which it again passes downwardly through the settling-

chamber. In cases where my system is employed as a steam generating system, cold water necessarily is added to the water within the system through the water-supply pipe 51 and as this 5 cold water comes in contact with the hot water circulating through the system, it immediately causes all the foreign matter within the water to settle to the bottom of the settling-chamber 40, where a blow-off pipe 53 is connected therewith, and at intervals this foreign matter is blown out of the system.

The rapid circulation of the water assured by this system eliminates the possibility of any foreign substances that may not have settled to 15 the bottom of the settling-chamber from adhering to the walls of the water-containing parts of the system, with the result that any such foreign substances failing to immediately settle to the bottom of the settling-chamber will, as they 20 reach the point at which the water-supply pipe 51 enters the settling-chamber, become separated from the circulating water and then settle to the bottom of said chamber. It is, of course, understood that the products of combustion come in 25 contact with the front and rear legs of the boiler proper and also in contact with the water-chambers, and that a certain degree of heat from the burning fuel is also transferred to the water within the water-jackets at the sides of the boiler-furnace. This rapid circulation of the water 30 through the boiler aids in keeping the boiler clean and will generate steam much quicker, and this is materially aided by delivering extra cooler or cold water into a settling-chamber a suitable distance from its bottom and delivering the water 35 from said settling-chamber into the boiler from approximately the same level, at least in part, as the feeding of water into the settling-chamber, and then returning it from the boiler at a high 40 point of the settling-chamber. The delivery of the cold water into the settling-chamber and the bringing of such water into contact with the hot water in circulation causes immediate separation of a major portion of foreign matter in the 45 entering cold water and also any foreign matter in the circulating hot water. All such foreign matter will gravitate to the bottom of the settling-chamber to be blown off in the usual manner, when desired.

50 The connection medially to the settling chamber 40 of the water-supply pipe 51 from the source of water supply and the water-feed pipe 43 leading from said settling chamber to a low point of the water within the boiler proper, eliminates all 55 interior walls and other parts or objects usually employed in settling chambers or other elements serving substantially the purpose of settling chambers. This, therefore, simplifies the construction of the settling chamber, reduces the cost 60 of same, and assures an effective action in separating foreign matter from the water before entering the boiler.

Having thus described my invention what I claim is:

65 1. The combination of a boiler having a tubular upper portion through the tubes in which the products of combustion may pass and from the lower end of which two spaced-apart depending water legs are arranged serving as the front and 70 rear of the combustion-chamber, water-chambers serving as the sides of the combustion-chamber and extending from front water leg to rear water leg, a settling-chamber, a pipe connecting the tubular portion of said boiler with the upper end of said settling-chamber, pipes connecting 75

said settling-chamber with the lower ends of said water-chambers, a pipe connecting said settling-chamber with the lower end of one of said water legs, pipes connecting the upper ends of said water-chambers with the tubular portion of said boiler, a pipe connected to said settling-chamber a distance from its lower end to feed water to said settling-chamber at a lower temperature than the water circulating therethrough by reason of its connection with said boiler and water-chambers, the cooler water entering said settling-chamber and coming in contact with the hot water in circulation and at such point of contact causing separation of foreign matter by the commingling of water and gravitation of such matter to the bottom of said settling-tank.

2. The combination of a boiler having a cylindrical tubular upper portion and spaced-apart depending water legs at its lower portion, water-chambers extending from one of said water legs to the other and spaced apart to form a combustion-chamber therebetween, a grate at the lower end of said combustion-chamber, water-jackets exterior of and spaced from said water-chambers to provide side fuel-chambers, grates at the bottom of said fuel-chambers, all mentioned grates being spaced from the bottoms of said water-chambers to permit the passage of fuel from said fuel-chambers to said first-mentioned grate, a settling-chamber spaced from said boiler, a water-supply pipe connected to said settling-chamber for the admission of cold water thereto at a point a distance from its bottom, connection between at least one of said water legs and said settling-chamber at approximately the level of said water-supply pipe, pipes connecting low points of said water-chambers with said settling-chamber, pipes connecting said settling-chamber with the lower ends of said water-jackets, connection between the upper ends of said water-chambers and the tubular upper portion of said boiler, connection between the upper ends of said water-jackets with the tubular upper portion of said boiler, and a pipe connecting the tubular upper portion of said boiler with the upper end of said settling-chamber and having a capacity approximately that of all pipes leading from said settling-chamber to said boiler, water-chambers and water-jackets.

3. The combination of a boiler provided with a fire box and segregated water-spaces surrounding said fire box and in circulating connection with the water in the upper portion of said boiler, a settling-chamber having a supply-pipe connected thereto a distance from its lower end for the admission of water at a lower temperature

than the water in said boiler, a blow-off pipe at the lower end of said settling-chamber, pipes connecting said settling-chamber at approximately the level of said supply-pipe with low points of the segregated water-spaces of said boiler, and a pipe of at least the capacity of said connecting pipes connecting a high point of said boiler with the upper end of said settling-chamber.

4. The combination of a boiler having a tubular upper portion with spaced-apart water legs depending from the lower end of said tubular portion at the front and rear thereof and between which legs a combustion chamber and water spaces are arranged, a settling chamber having connection at its upper end with the tubular portion of said boiler, connection at a comparatively low point of said settling chamber with the lower end of at least one of said depending legs, connection between said settling chamber and low points of said water spaces, connection between high points of said water spaces and the tubular portion of said boiler, said tubular portion, water spaces, settling chamber and connections providing means for circulating the water through the boiler and settling chamber, and a pipe connected to said settling chamber for admission of cooler water than the water in circulation, said pipe entering said settling chamber a distance above the bottom thereof and serving to bring the cooler water in contact with the hot water in circulation to cause separation of foreign matter and to cause the same to gravitate to the bottom of said settling chamber.

5. The combination of a boiler having a cylindrical tubular upper portion and spaced apart depending water legs at its lower portion, water chambers extending from one of said water legs to the other and being spaced apart to form a combustion chamber therebetween, a grate at the lower end of said combustion chamber, a settling chamber spaced from said boiler, a water supply pipe connected to said settling chamber for the admission of cold water thereto at a point a distance from its bottom, connection between at least one of said water legs and said settling-chamber at approximately the level of said water supply pipe, pipes connecting low points of said water chambers with said settling chamber, connections between the upper ends of said water chambers and the tubular portion of said boiler, and a pipe connecting the tubular portion of said boiler with the upper end of said settling chamber and having a capacity approximately that of all pipes leading from said settling chamber to said boiler.

JOHN COOK.
